(57) **CLAIM**

The ornamental design for a CPAP device as shown.

DESCRIPTION

FIG. 1 is a top perspective view of a first embodiment of the CPAP device, showing our new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof;

FIG. 8 is a bottom perspective view thereof;

FIG. 9 is a top perspective view of a second embodiment of the CPAP device, showing our new design;

FIG. 10 is a front elevational view thereof;

FIG. 11 is a rear elevational view thereof;

FIG. 12 is a right side elevational view thereof;

FIG. 13 is a left side elevational view thereof;

FIG. 14 is a top plan view thereof;

FIG. 15 is a bottom plan view thereof;

FIG. 16 is a bottom perspective view thereof;

FIG. 17 is a top perspective view of a third embodiment of the CPAP device, showing our new design;

FIG. 18 is a front elevational view thereof;

FIG. 19 is a rear elevational view thereof;

FIG. 20 is a right side elevational view thereof;

FIG. 21 is a left side elevational view thereof;

FIG. 22 is a top plan view thereof;

FIG. 23 is a bottom plan view thereof;

FIG. 24 is a bottom perspective view thereof;

FIG. 25 is a top perspective view of a fourth embodiment of the CPAP device, showing our new design;

FIG. 26 is a front elevational view thereof;

FIG. 27 is a rear elevational view thereof;

FIG. 28 is a right side elevational view thereof;

FIG. 29 is a left side elevational view thereof;

FIG. 30 is a top plan view thereof;

FIG. 31 is a bottom plan view thereof; and,

FIG. 32 is a bottom perspective view thereof.
